CANDELABRUM OR THE LIKE

Carl A. Frost, Wheaton, Ill.

Application April 9, 1959, Serial No. 55,416

Term of patent 14 years

(Cl. D48—2)

FIG. 1

FIG. 2

Figure 1 is a front elevational view of a candelabrum or like article, embodying my new design, and showing the supporting members in both full and broken lines to indicate a plurality of such members along the length of the standard which is shown to be of indeterminate length.

Figure 2 is a sectional view of the candelabrum or the like taken along the line 2—2 of Figure 1.

I claim:

The ornamental design for a candelabrum or the like, as shown and described.
